Walter Murray
Inventor

United States Patent Office.

WALTER MURRAY, OF CHICAGO, ILLINOIS.

Letters Patent No. 92,634, dated July 13, 1869.

IMPROVEMENT IN BOOTS AND SHOES.

The Schedule referred to in these Letters Patent and making part of the same.

To all whom it may concern:

Be it known that I, WALTER MURRAY, of Scotland, resident of the city of Chicago, in the county of Cook, and State of Illinois, have invented certain new and useful Improvements in "Boots and Shoes," and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

Figure 1 represents the section of the boot, and

Figure 2 is the top view of the inner sole and heel.

The object of my invention being to improve the appearance of the foot when clothed in a boot or shoe,

Its nature consists in providing the boot or shoe with an inner heel, so arranged that the foot stands always in natural posture, and comfortably, inside of such a boot or shoe; also in bringing, by the said inner heel, the outer heel of the boot or shoe down, whereby the shank of the same becomes curved upwards, showing the foot with a high instep.

The improvement consists also in the mode of attaching the metallic spring, strengthening the shank of the boot or shoe to the insole and the said inner heel of the same, in such a manner as to adapt the said shank to the foot of any shape, that is, flat or hollow.

A is the inner heel or cork, presenting itself a gradual enlargement in thickness of the insole E, to the rear of the boot or shoe. It may be made higher or lower, according to the shape of the foot, and to the object of forming a higher or lower instep.

It is made of leather, cork, or any other suitable material, and so arranged, in combination with the in-

sole E, that the foot B rests on the said inner heel and the insole in a natural position.

C is a curved metallic spring, single or double, riveted, or otherwise secured, at the rear, to the inner heel A, and provided with a slot, d, at the front end, through which slot passes pin f of the metallic plate F, riveted to the insole E, the spring C having the purpose of strengthening and of giving a curvature to the shank G of the boot or shoe.

The plate F protects the insole from rapid wearing by the fore end of the spring C, while the slot d, cut lengthway in the spring, allows the spring to play, and thus to accommodate itself to the foot of any shape, flat or hollow.

The above description shows that by the arrangement of the inner heel A, as described, the foot always preserves an easy, natural, and comfortable position in the boot or shoe, while the shank of the boot or shoe, having no strain whatever, is kept, by the spring C, always in the same curved shape, and makes the foot to present, in outward appearance, a high instep, and to appear smaller than it really is.

Being aware that metallic springs, for the purpose of shaping the shanks of boots and shoes, are in use, what I claim as new, and desire to secure by Letters Patent, is—

1. The spring C, having its rear end attached rigidly to the heel, and having its front end secured to the sole by means of the spur f and the slot d, substantially as and for the purpose set forth.

2. The inner heel A, constructed and applied, as shown and described, for the purpose of giving greater curve to the sole, as set forth.

WALTER MURRAY.
